UNITED STATES PATENT OFFICE.

HOMER EARL, OF HASTINGS, NEBRASKA.

IRRIGATION PUMP.

Application filed October 21, 1927. Serial No. 227,792.

My present invention has reference to a centrifugal irrigation pump and my object is the provision of a pump of this type and for this purpose that shall comprise few simple parts and which will successfully discharge water in a large volume with a comparatively small expenditure of motive power.

A further and important object is to construct a pump of this type in which the casing performs the dual purpose of a curb and discharge pipe, the said casing having a lower perforated portion which is sunk below the water line and having its top portion provided with water outlets and a cap disposed over the said top portion through which is journaled the shaft of an impeller of a particular, peculiar and novel design, there being adjustably arranged in the casing a notched ring that provides a support for the saddle for the impeller and the suction pipe being connected to and communicating with the lower end of the saddle and with the blades of the impeller.

A further object is the provision of a device for this purpose in which an impeller and a saddle therefor constitutes the pump, both the saddle and the impeller being inserted in the discharge pipe which also constitutes the curb for the well, and in which the employment of a volute and extra discharge pipe and frame for holding the same is entirely dispensed with, and further in which a single thrust bearing at the top of the well provides a support for the shaft of the impeller.

The improvement also resides in other novel features of construction, combination and operative association of parts, one satisfactory embodiment of which is disclosed by the accompanying drawings.

In the drawings:

Figure 1 is an elevation, with parts broken away and parts in section of my improvement.

Figure 2 is a sectional view approximately on the line 2-2 of Figure 1.

Figure 3 is a perspective view of the support for the saddle.

The casing 1 of the improvement is made up of any desired number of sections, all of the said sections being of the same diameter. The lower end of the casing is provided with annular series of apertures 2. This portion of the casing is arranged below the water line so that the apertures provide water inlets to

the casing. The casing, it is to be noted provides the discharge pipe for the well. The casing 1, above the ground level has circumferentially arranged spaced series of 60 openings 3 therethrough and these openings afford water outlets. The top of the casing is closed by a flanged cap member 4, the said cap at the center thereof being provided with a round opening that is surrounded by oppositely extending flanges 5, the said flanges in reality affording the top or cap 4 with a hub through which is journaled the shaft 6 for the impeller. The shaft 6 has fixed on its outer end a wheel 7 for a belt or for other means for rotating the shaft. The wheel 7 may rest directly upon the outer end of the hub 5, or there may be suitable anti-frictional bearings (not shown) between the said hub and wheel. The hub it will be noted serves 75 as a thrust bearing for the wheel.

Before the cap is arranged in position and before the shaft 6 is journaled through the hub of the cap, I arrange in the casing 1 a ring member 8. This ring member may be 80 secured adjusted in the casing by any desired means. The ring 8 has its upper edge provided with spaced notches 9, and these notches are designed to receive therein offset fingers or lugs 10 that project from the upper edge 85 of the saddle 11 of the improvement. The saddle has its body portion substantially cup-shaped and its bottom formed with an opening that is surrounded by a tubular extension 12. On the bottom of the saddle, the 90 said extension 12 has a thickened portion at its outer end that affords an inner shoulder 13. The thickened portion of the annular flange or pipe member is interiorly threaded and has screwed therein the upper end of 95 the suction pipe 14.

Splined as well as fixed on the shaft 7 through the medium of an adjustable element 15 there is the upper and sleeve end 16 of the impeller 17. The impeller is hollow and is 100 of substantially pear-shape formation. The rounded bottom of the impeller provides inner and outer spaced walls 18 and 19 respectively, the inner wall having a central opening therethrough surrounded by an inwardly directed flange 20 that receives therein the lower end of the fixed shaft 6. Between the inner and outer rounded walls 18 and 19 of the impeller 17 there are curved blades 21. By reference to Figure 1 of the drawings it will 105 be noted that the walls 18 and 19 that provide the water ducts for the blades 21 are gradual-

ly spaced away from each other from their upper to their lower portions so that the greater volume of water from the suction pipe 14 will enter the lower and widened passage between the walls 18 and 19 and after being acted upon by the curved blades 21 will be forcibly ejected upwardly through the restricted passage between the said walls 18 and 19.

10 The outer wall 19 which forms the base of the impeller is snugly received in the bore of the cup-shaped saddle 11, but only slightly contacts therewith so that the same is freely rotatable in the saddle. The wall 19 is 15 formed with an annular extension 23 whose end is disposed directly over the shoulder 13 of the saddle. The annular extension 23 is provided on its outer face with spaced continuous grooves 24 and these grooves afford a 20 water cushion or a water lubricant between the impeller and the saddle. There is no undue frictional engagement between the impeller and the saddle, as the wheel 7 for the shaft 6, resting upon the thrust bearing provided by the hub 5 hold the said impeller and saddle in only slight contacting engagement which will in no way interfere with the free turning of the impeller.

My improvement employs less parts and is 30 of a simpler nature than the centrifugal pumps for the same purpose. The advantages of my construction will, it is thought, be readily apparent to those skilled in the art to which such invention relates so that further detailed description is not thought necessary. Obviously I do not wish to be restricted to the precise details of my improvement as herein set forth and, therefore, hold myself entitled to such changes therefrom as 40 fairly fall within the scope of what I claim.

Having described the invention, I claim:

1. A centrifugal irrigation pump comprising a casing having an apertured lower portion designed to be sunk below water level 45 and having water outlets adjacent to its top, and said casing comprising a flow pipe, an impeller mounted to revolve in the casing, a saddle in which the lower end of the impeller is snugly received for rotation, and the upper 50 portion of the saddle having outstanding lugs, a ring member removably and adjustably secured in the casing and having notches to receive the lugs of the saddle therein, a suction pipe connected to and depending from

the lower portion of the saddle and entering 55 the apertured portion of the casing, said suction pipe being in a line with the blades of the impeller.

2. A centrifugal irrigation pump comprising 60 a casing having an apertured lower portion designed to be sunk below water level and having water outlets adjacent to its top, a flanged cap closing the top of the casing and having a central hub portion, a shaft journaled through the hub and entering the casing, a wheel fixed on the outer end of the shaft, and resting on the hub, an impeller removably and adjustably fixed on the shaft, 65 said impeller comprising a substantially pear-shaped hollow member and having its rounded bottom comprising inner and outer spaced walls, and curved blades connecting the walls, a substantially cup-shaped saddle in which the outer wall of the impeller is snugly and freely received for rotation, a removable and 70 adjustable support in the casing for the saddle and a suction pipe secured to the lower end of the saddle and arranged in a line with the blades of the impeller.

3. A centrifugal irrigation pump comprising 75 a casing having an apertured lower portion designed to be sunk below water level and having water outlets adjacent to its top, a flanged cap closing the top of the casing and having a central hub portion, a shaft journaled through the hub and entering the casing, a wheel fixed on the outer end of the shaft and bearing on the hub, an impeller removably and adjustably fixed on the shaft, 80 said impeller comprising a substantially pear-shaped hollow member and having its rounded bottom comprising inner and outer spaced walls, and curved blades connecting the walls, the outer wall having a depending 85 annular portion provided with outer continuous grooves, a cup-shaped saddle freely and snugly receiving the outer and lower wall of the impeller therein, a removable and adjustable support in the casing for the saddle, 90 said saddle having its lower end formed with an annular extension provided with an inwardly directed shoulder which is disposed adjacent the end of the extension on the impeller, and a suction pipe screwed in the said 95 extension of the saddle.

In testimony whereof I affix my signature.

HOMER EARL.
